UNITED STATES PATENT OFFICE

142,803

DESIGN FOR A TOY OR SIMILAR ARTICLE

George Winston and Albert B. Sawyer, Brooklyn,
N. Y., assignors to Plastic Treasures Inc., New York, N. Y.

Application July 3, 1945, Serial No. 120,500

Term of patent 7 years

(Cl. D34—15)

To all whom it may concern:

Be it known that we, George Winston and Albert B. Sawyer, citizens of the United States of America, both residents of Brooklyn, New York, have invented a new, original, and ornamental Design for a Toy or Similar Article, of which the following is a specification, reference being had to the accompanying drawing, forming a part thereof.

Fig. 1 is a front view of a toy showing our new design;

Fig. 2 is a side view thereof.

We claim:

The ornamental design for a toy or similar article, as shown.

GEORGE WINSTON.
ALBERT B. SAWYER.
